ABSTRACT OF THE DISCLOSURE

A fluid readout and storage device has a cavity within which there is a floating body in the form of a ball. At each end of the cavity are valve seats surrounding end openings, while centrally located in the cavity is a lateral opening. Air is blown through perforations in a tape or card, which perforations register with the cavity lower end opening through a check valve which air passes out the lateral opening to raise the floating body above the lower seat. Thereafter air under pressure is introduced into the lateral opening, closing the check valve and holding the floating body against the upper seat. At stations where there are no perforations in the tape the floating body remains on its lower seat. The position of the floating bodies thus stores the information as to where there were perforations in the tape and where there were not. This stored up information is read out electrically by the floating body bridging electrical contacts at the seats.

The present invention relates to a device for pneumatic or hydraulic storage of information from perforated information carriers such as perforated tape or punched cards, wherein a fluid flow is either interrupted by the information carrier (if there is no hole in the carrier at the respective location) or is released by a hole in the information carrier. In the prior art arrangements the pressure of the fluid downstream or upstream of the information carrier is utilized as a criterion for the presence or absence of a hole in the information carrier. If, for instance, a channel carrying the air current (and formed with a throttle) is covered by the information carrier the pressure will be high since the air finds it hard to leave. If, however, there is a hole provided at the observed spot of the information carrier, then in that instance air is free to escape. The pressure drop occurs at said throttle and the pressure in the channel downstream of the throttle decreases substantially to atmospheric pressure. However, this state is maintained only for the time that the information carrier has an opening at the observed spot. To store the information, a pneumatic electric transducer must be provided and the electric signal obtained therefrom must be stored electrically, for instance, in a flip-flop. The prior art arrangement requires a relatively large amount of apparatus.

It is therefore the object of the present invention to provide an arrangement for readout and storage of information from a perforated information carrier, which is simple in design and wherein an information is not only readout but also stored by means of a fluid. According to the invention this object is attained by providing a floating body movable between two opposed valve seats between which fluid can optionally be supplied or discharged through one or several lateral openings. The floating body is either raised above the lateral opening by the fluid flow controlled by the information carrier or contacts the lower valve seat.

Thus, it is not the pressure upstream of the information carrier that is utilized as output quantity, but rather the

2

position of a floating body. If the fluid flow does not apply a dynamic pressure on the floating body, the floating body bears against the lower valve seat. Upon readout the lateral openings connect to low pressure. If there is a fluid flow to the floating body, this will raise the floating body and permit the fluid to flow to the lateral opening for discharge. Subsequently, the arrangement may be changed over to "storing" by now supplying higher pressure through the lateral opening.

If there were no hole in the information carrier, the floating body would remain on its lower valve seat during the preceding readout action and the fluid supplied through the lateral opening will not effect any change. However, if the floating body had been raised from the

15 valve seat into a position above said lateral opening, then the pressure urges the floating body upwardly against the upper valve seat. The floating body will remain in such position as long as the storing pressure continues from said lateral openings.

20 The control of the fluid flow by the information carrier may be arranged so that the floating body is downstream of the information carrier in path of fluid flow. In such case the fluid flow will be released and the floating body be raised when there is a hole in the information carrier

25 at the spot scanned. However, it is also possible that the fluid flow is supplied between the information carrier positioned in front of an outlet opening and the floating body. In such case the fluid flow discharges outwardly into the atmosphere when there is a hole present in the information carrier.

30 There will be no pressure exerted on the floating body so that the latter bears against its lower valve seat. With such an arrangement the floating body will be raised when the information carrier has no hole and covers the outlet opening.

35 Provision may be made for the valve seats to form electrical contacts with the circuit therebetween being closed by the floating body. Thereby, a stored electric output is also obtained without further flip-flops or the like.

40 It is expedient to have a relief valve arranged upstream of the floating body. This relief valve will also be raised by the fluid flow if there is a hole present in the information carrier. During information storage, when the floating body is urged upon the upper valve seat, the relief valve is

45 forced onto its seat, thereby preventing an escape of the storage pressure in a direction towards the information carrier. Therefore, it is possible to operate with relatively small fluid quantities for storage and still safely maintain the floating body on its upper valve seat.

50 Embodiments of the invention may provide for parallel readout and storage of a plurality of information several channels with floating bodies and openings for optional fluid supply or discharge positioned side by side and/or one behind the other. This does not represent any substantial amount of apparatus. One specific address may be associated with each interrogation channel so that an additional transfer of an address—in the form of punched information—may be avoided for each item of information actually to be processed.

60 An embodiment of the invention is presented in the drawings and described as follows:

FIG. 1 illustrates a section through a device according to the invention with a perforated tape in the state of "readout."

65 FIG. 2 illustrates the same device in the state of "storing."

70 FIG. 3 is a section at line 3—3 of FIG. 1 showing the valve seats and the electric contacts utilized with the arrangement of FIGS. 1 and 2.

FIG. 4 illustrates a further embodied form of the invention.

FIG. 5 schematically illustrates an air supply system. FIGURES 1 and 2 illustrate a portion of an apparatus for simultaneously, and in parallel, reading out five bits of information from a perforated tape 10. Thus there are five readout channels, or scanning spots identified by letters A, B, C, D and E. In the illustrated embodiment the tape 10 has openings 22 at scanning spots B, D and E. There are no holes in the tape at scanning spots A and C.

A bottom plate 23 has a fluid inlet 24 through which fluid under pressure is supplied to a groove or channel 26. The portion of tape 10 in which the openings 22 appear (or are absent) overlies groove 26. Above the perforated tape is a plate 28 having a cavity 30 for each scanning spot. Each of these cavities has an opening 32 extending through the bottom of plate 28 in alignment with the respective scanning spot. The bottom of the cavities 30 are conical forming valve seats 33. These valve seats, in conjunction with balls 34 form relief valves.

A plate 36 is mounted on plate 28. Plate 36 has a relatively narrow bore 38 at each scanning spot in communication with cavity 30. Plate 36 is formed in the manner of a printed circuit, as best seen in FIG. 3. At opposite sides of holes 38 are contacts 40 and 42 having connecting leads 44.

Mounted on plate 36 is a second thick plate 46 having cavities 48 in communication with the respective bores 38. Each of these upper cavities has a flat annular groove 50 thereabout, which groove communicates with a respective pressure inlet or outlet channel 54 through a lateral opening 52. A top plate 56 abuts plate 46 with openings 57 in communication with cavities 48. The bottom face of plate 56 is formed (like the top face of plate 36) in the manner of a printed circuit with pairs of electrical contacts 58 and 60. In each of cavities 48 are floating bodies formed by balls 62.

During a "readout" operation channels 54 communicate with low, e.g. atmospheric, pressure through control means comprising conduit 53 and two-way valve 55 (FIG. 5). As previously stated, fluid under pressure is supplied to inlet 24.

At the channels or spots at which there is no opening 22 in tape 10, the lower balls 34 remain on their respective seats 33. Thus in the arrangement illustrated in FIG. 1, balls 34 of channels A and C are on their seats. At the same time the corresponding upper balls 62 of channels A and C remain in the lower position closing an electrical circuit between contacts 38 and 42. If a "storing" operation now is to be performed, air under pressure is supplied to channels 54 from source 59 through valve 55 and conduit 53 (FIG. 5). This air under pressure escapes through the upper openings 57 of channels A and C, as illustrated in FIG. 2. Since balls 62 form electrical circuits between contacts 38 and 42 an electrical readout of this situation in channels A and C may be made.

At those channels at which there are openings 22 in tape 10, the pressure initially applied through inlet 24 forces balls 34 off of their lower seats 33. As is illustrated in channels B, D and E of FIG. 1, this same air flow raises balls 62 off of plate 36 and upwardly in the respective cavities 48 to a position at which the balls clear channel 54. Now when fluid under pressure is supplied to channels 54 in the "storing" operation, this fluid has two effects; (1) balls 34 in channels B, D and E are forced downwardly onto their seats 33, and (2) balls 62 in the same channels are forced upwardly over openings 57 in plate 56. So long as pressure is maintained in channels 54 the balls will remain in this position. The balls bearing against plate 56 bridge electrical contacts 58 and 60 of the respective channel to form an electrical circuit.

The situation during such a "storing" operation is illustrated in FIG. 2. The bridging of the upper contacts 58 and 60 at channels B, D and E indicate the existence of openings 22 in tape 10 at the respective scanning spots. The bridging of contacts 38 and 42 at channels A and C

produce electrical signals indicating that no perforations exist in tape 10 at the respective scanning spots. These electrical signals may be read into the memory of a data processing machine, for example.

During storing by the feed of the information carrier the next readout action may be expediently prepared, thereby enabling a particularly quick readout.

FIG. 4 likewise illustrates a five channel device for simultaneous readout and storage of five information bits from a tape 78. In this embodiment the channels are designated F, G, H, I and J respectively. As illustrated, there are openings 74 and 76 in tape 78 at the scanning spots defined by channels F and H respectively. There are no holes at the scanning spots defined by channels G, I and J.

Tape 78 is carried between two plates 80 and 82. At the scanning spots, plate 80 has bores 84 communicating with atmosphere. Opposite bores 84 are bores 86 in plate 82 which open into cavities 88. At the juncture of bores 86 and cavities 88 there are flared walls forming valve seats 87.

Lateral openings 92 communicate respectively with bores 86 and pressure channels 94.

Plate 96 abuts plate 82. Plate 96 has a plurality of bores 98 in communication with cavities 88. Plate 100 has cavities 102 in communication with bores 98. Balls 104, forming floating bodies, are received in cavities 102. A plate 105 having small bores 106 is mounted on plate 100. Plates 96 and 105 form two superposed valve seats 30 for balls 104.

During a "readout" operation, fluid under pressure is supplied to pressure channels 94, while bores 84 are open to atmosphere. At the channels at which are positioned openings in tape 78 this fluid flows freely from the pressure channel to atmosphere, as is illustrated with respect to channels F and H in FIG. 4. Thus balls 90 and 104 of channels F and H remain on their lower seats. At locations where tape 78 does not have openings, the fluid under pressure flows upward through the two cavities 88 and 102. This flow of fluid raises balls 90 and 104, as is illustrated with respect to channels G, I and J.

To perform a "storing" operation, fluid under a higher pressure is supplied to channels 110. This higher pressure fluid forces balls 104 of channels G, I and J upwardly 45 against their upper seats formed by plate 105. Thus in the storing operation balls 104 will be on the seats defined by plate 96 at channels at which there is an opening in tape 78 (channels F and H), while the balls 104 will be on the seats defined by plate 105 at channels at which 50 there is no opening in tape 78 (channels G, I and J). Whether the ball 104 is against its upper seat or against its lower seat may be determined by electrical circuits formed through the balls and through the electrical contacts in plates 96 and 105 in the manner described in 55 respect to FIGS. 1-3.

The invention claimed is as follows:

1. In a device for the fluid readout and storage of information from a coded perforated information carrier wherein a first fluid flow is rendered effective or non-effective under the control of the information carrier, the improvement comprising: body means having a cavity with opposed openings, said body means defining valve seats about said openings, said body means having lateral opening means in said cavity between said seats through 60 which fluid can be optionally supplied to and discharged from said cavity; a floating body in said cavity and movable between the opposed seats; and means communicating with said first fluid flow and a first of said seats for positioning said floating body generally between said lateral opening means and one of said seats when said first fluid flow is effective and said fluid is discharged from said lateral opening means and generally between said lateral opening and the other of said seats when said first fluid flow is non-effective whereby when fluid is then supplied 65 to said lateral opening means said body means between 70 opening means and one of said seats when said first fluid flow is effective and said fluid is discharged from said lateral opening means and generally between said lateral opening and the other of said seats when said first fluid flow is non-effective whereby when fluid is then supplied to said lateral opening means said body means between 75 opening means and one of said seats when said first fluid flow is effective and said fluid is discharged from said lateral opening means and generally between said lateral opening and the other of said seats when said first fluid flow is non-effective whereby when fluid is then supplied to said lateral opening means said body means between

said lateral opening means and said one of said seats will be moved against the one of said seats and said body means between said lateral opening means and said other of said seats will be moved against said other of said seats.

2. In a device as set forth in claim 1, wherein the communicating means receives said first fluid flow after passing through said carrier and directs it into said cavity.

3. In a device as set forth in claim 1, wherein the communicating means receives said first fluid flow blocked off by said carrier and directs it into said cavity.

4. In a device as set forth in claim 1, wherein said communicating means includes a check valve through which said first fluid flow passes in reaching said cavity.

5. In a device as set forth in claim 1, wherein the body means forms a pair of electrical contacts at each of said seats respectively, and an electrical circuit is made across the pair at one seat when the floating body is at the one seat and across the pair at the other seat when the floating body is at the other seat.

6. In a device as set forth in claim 5, wherein said body means is formed of a plurality of plates with two of said plates defining said opposed openings and seats, said two plates having said contacts therein in the form of printed circuits, said floating body being a conductor of electricity.

7. In a device as set forth in claim 6, wherein another of said plates is in juxtaposition to one of said two plates, said third plate having a first opening communicating with said cavity and a second opening in communication with said carrier at the point at which the information is coded with said information carrier, and including a check valve between said first and second openings in said third plate to normally prevent fluid flow from said cavity out of said second opening.

8. In a device as set forth in claim 7, wherein fluid under pressure is supplied to said second opening between said carrier and said check valve to form said first fluid flow.

9. In a device as set forth in claim 7, wherein fluid under pressure is supplied through said information carrier to said second opening to form said first fluid flow.

10. In a device for fluid readout and storage of information from a coded perforated information carrier wherein a first fluid flow is rendered effective or non-effective under the control of the information carrier and for use with a source of fluid under pressure, the improvement comprising:

a body having a cavity with openings at opposite ends of the cavity and a lateral opening communicating with the cavity intermediate said ends thereof, said body defining a valve seat about each of said end openings;

floating body means in said cavity and normally posi-

tioned in juxtaposition to a first of said seats while being movable through said cavity into a position in juxtaposition to a second of said seats, said floating body means being of a size to obstruct fluid flow through said first seat when in juxtaposition thereto and to obstruct fluid flow through said second seat when in juxtaposition thereto;

control means communicating with said lateral opening for placing it alternatively in communication with exhaust and with said source of fluid under pressure, whereby when said floating body means is in said normal position and fluid under pressure is applied to said lateral opening from said source said floating body means will be forced against said first seat and when said floating body means is positioned generally between said lateral opening and said second seat and fluid under pressure is applied to said lateral opening from said source said floating body means will be forced against said second seat; and means communicating with said first fluid flow and said first seat for positioning, when said control means is set to communicate said lateral opening with exhaust, said floating body means into said position generally between said lateral opening and said second seat when said first fluid flow is effective.

11. In a device as set forth in claim 10, wherein said body is positioned so that said first seat is at the bottom of the cavity and said second seat is at the top of the cavity.

12. In a device as set forth in claim 11, wherein the last mentioned means includes a check valve upstream, with respect to said first fluid flow, of said first seat, said check valve being arranged to permit fluid flow therethrough in the direction of from it towards said first seat and to block fluid flow from the first seat towards the check valve.

13. In a device as set forth in claim 12, including means at each of said seats forming a pair of electrical contacts at each seat, said pair of contacts being positioned to be contacted by said floating body means when it is against the respective seat, said floating body means being a conductor of electricity.
